United States Patent Office.

WILLIAM EVANS, OF PITTSBURG, PENNSYLVANIA, ASSIGNOR TO HIMSELF
AND WILLIAM COLEMAN, OF SAME PLACE.

Letters Patent No. 99,074, dated January 25, 1870.

IMPROVEMENT IN CLIPS FOR ELLIPTIC SPRINGS.

The Schedule referred to in these Letters Patent and making part of the same.

To all whom it may concern:

Be it known that I, WILLIAM EVANS, of the city of Pittsburgh, in the county of Allegheny, and State of Pennsylvania, have invented a new and useful Improvement in Clips for Elliptic Springs; and I do hereby declare the following to be a full, clear, and exact description thereof, reference being had to the accompanying drawing, making a part hereof, in which—

Figure 1 is a perspective view of the barrel-part of my improved clip.

Figure 2 is a like view of the pin, and

Figure 3 is a sectional view of the clip, and of the end of an elliptic spring to which it is applied.

Like letters of reference indicate like parts of each.

My invention consists in the construction of an improved clip for elliptic vehicle-springs.

Description of the Invention.

The barrel *a* and pin *b* are made by casting, or in any other known way.

The barrel *a* has a close head at one end, as *a'*, with the exception of a hole, at or near its centre, for the pin *b*, and when the latter is in place its head *b'* closes the other end of the barrel *a*.

Extending lengthwise of the barrel *a* are two slots *c c*, of such form and relative position that the leaves *e e* of the spring may be inserted therein, and their hook-shaped ends *e'* engage the pin *b*, as illustrated in fig. 3.

The inner face of the head *b'*, and the corresponding end of the barrel *a*, may be fitted together with a bevelled joint, as at *s s'*, or other suitable joint, not flat, whereby one will be caused to take a firm hold on the other, so that they will, when in use, preserve the proper position with reference to each other, and lateral displacement be prevented. The opposite end of the pin *b* may be secured by a nut, or key, or by riveting, or in any other suitable way.

The chief advantages of the clip described are that it covers or boxes up the ends of the leaves, so as more perfectly to prevent their displacement or injury, and at the same time that part *x* of the barrel which is bounded by the slots *c c*, and comes between the leaves *e*, as shown in figs. 2 and 3, operates as a brace or support to the leaves, and thereby increases the carrying-capacity of the spring.

What I claim as my invention, and desire to protect by Letters Patent, is—

A barrel-shaped clip for elliptic springs, having slots *c c*, in combination with pin and cap, substantially as described.

In testimony whereof, I, the said WILLIAM EVANS, have hereunto set my hand.

WILLIAM EVANS.
